UNITED STATES PATENT OFFICE.

ISRAEL EISENSTEIN, OF NEW YORK, N. Y.

DESIGN FOR A SWAGGER-STICK.

54,727.

Specification for Design.

Patented Mar. 23, 1920.

Application filed May 26, 1919. Serial No. 299,991. Term of patent 7 years.

To all whom it may concern:

Be it known that I, ISRAEL EISENSTEIN, a citizen of the United States, residing at New York city, in the county of New York and State of New York, have invented a new, original, and ornamental Design for Swagger-Sticks, as shown in the accompanying drawing and described in the following specification.

Figure 1 is a perspective view of the swagger stick, showing my new design.

Fig. 2 is an enlarged side view of a portion of the stick to show in detail a feature.

The stick 2, has a shell shaped head 3 and a bullet shaped point 4. Just below the head is a design 5.

I claim—

The ornamental design for a swagger stick, substantially as shown, and described.

ISRAEL EISENSTEIN.
